(57) **CLAIM**

The ornamental design for mount for electronic devices, as shown and described.

DESCRIPTION

The file of this patent contains at least one drawing/photograph executed in color. Copies of this patent with color drawing(s)/photograph(s) will be provided by the Office upon request and payment of the necessary fee.

1. Mount for Electronic Devices

FIG. 1.1 is a front and side perspective view of a mount for electronic devices, embodying my new design;

FIG. 1.2 is a front and opposite side perspective view thereof;

FIG. 1.3 is a top plan view thereof;

FIG. 1.4 is an another top plan view thereof, with the mount shown in an alternate position; and

FIG. 1.5 is a bottom and front perspective view thereof.
